UNITED STATES PATENT OFFICE.

JOHN F. O'CONNOR, OF CHICAGO, ILLINOIS, ASSIGNOR, BY MESNE ASSIGNMENTS, TO
W. H. MINER, INC., A CORPORATION OF DELAWARE.

CAR CONSTRUCTION.

Application filed September 28, 1923. Serial No. 665,311.

This invention relates to improvements in car construction.

One object of the invention is to provide a simple, efficient and relatively inexpensive arrangement which is particularly adapted for mine cars of the type most commonly employed, effective to cushion the shocks in buff and wherein provision is made for coupling the cars in a simple manner.

Other objects and advantages of the invention will more clearly appear from the description and claims hereinafter following.

In the drawing forming a part of this specification, Figure 1 is a vertical, longitudinal, sectional view of the adjacent ends of two mine cars showing my improvements in connection therewith. And Figure 2 is a top plan view of the structure illustrated in Figure 1.

In said drawing, each mine car is shown as provided with a heavy flooring 10 and a vertical end wall 11. At the opposite ends each car is also provided with a drawbar 12.

Each drawbar is in the form of an elongated flat plate extending through the end wall 11 and secured to the inner end of the flooring 10. Adjacent the outer end, each drawbar is provided with a downwardly pro-

jecting lug 13 abutting the vertical arm of an angle plate 14 fixed to the end of the car by bolts 15 extending through the upper end of the angle plate and the flooring 10, the upper arm of the angle plate being cut

away at the center to accommodate the horizontal portion of the drawbar 12. A bolt 16 extending through the drawbar, the outer end of the flooring 10 and a transversely ex-

tending reinforcing member 17 at the under side of the flooring, is preferably provided to secure the outer end of the drawbar to the car.

In carrying out my invention, I provide a spring buffer A at each end of the car.

Each of the buffers A is in the form of an open loop of bar spring steel, having an outer curved section 18 of relatively great radius; opposite curved end sections 19-19 of relatively short radius terminating in aligned straight sections 20-20, the latter being riveted or otherwise secured to the vertical arm of the corresponding angle plate.

The drawbars at the opposite ends of the

car each have a block B swiveled thereto, the blocks B at the opposite ends of the car being of like construction. The blocks B are each provided with a centrally disposed, upwardly projecting cylindrical stem 21 and the projecting end of each drawbar is provided with an opening 22 adapted to receive the stem of one of the blocks. The stem of each block serves to swivelly connect the same to the corresponding drawbar, the block being suspended below the drawbar by the stem 21 which projects above the drawbar and has a nut 23 secured on the upper end thereof bearing on the upper surface of the drawbar. Each of the blocks B is thus supported within the corresponding spring loop A and has the upper surface thereof in bearing contact with the under surface of the corresponding drawbar.

To couple the cars, a link C and a hook D are provided, the link being pivoted to the block B at one end of the car and the hook to the block D at the opposite end of the other car; the cars being always so disposed when coupled that the link on one car is in opposed relation to the hook of the adjacent car.

Each link C is preferably of U shape and has the side arms thereof thickened at the open end of the U as indicated at 24, said thickened portions being perforated to receive a horizontally disposed pivot pin 25 extending through the corresponding block B, thereby supporting the link for swinging movement in a vertical plane. The pin is preferably retained in position by a cotter pin.

Each hook D has the rear end of the shank thereof bifurcated as indicated at 26, thereby providing a pair of arms 27-27, straddling the corresponding block B. A horizontally disposed pivot pin 28 extending through the block B and the arms 27 serves to pivotally support the hook for swinging movement in a vertical plane. The arms 27-27 are preferably thickened adjacent the pivot openings thereof to strengthen the same, the pin being preferably retained in position by a cotter pin. The hook member proper of the hook D is directed downwardly and the engaging end thereof inturned slightly as indicated at 29 to prevent accidental disengagement thereof.

When the hook D is disengaged from the

link C in uncoupling the cars, both the hook and the link may be dropped down, assuming a pendant position, thereby providing proper clearance when the car is in a restricted space, as when the same is being handled on the mine hoist.

In buffering action it is evident that, as the cars approach each other, the spring buffers A of the adjacent cars will be brought into abutment and the loops compressed, thereby absorbing the buffering shocks. While the cars approach each other during buffering action, the hook and link will swing downwardly on their pivots but will remain interlocked due to the engaging end of the hook proper being inturned:

I have herein shown and described what I now consider the preferred manner of carrying out my invention; but the same is merely illustrative, and I contemplate all changes and modifications that come within the scope of the claims appended hereto.

I claim:

1. In a device of the character described, the combination with the end structure of a car, including a draw bar; of a resilient element having a centrally bowed portion spaced outwardly from the end of said draw bar, said resilient element having looped side portions and inwardly turned end portions secured to the car structure inwardly of the outer end of said draw bar; and a coupling element operatively associated with said draw bar and arranged to extend outwardly of said resilient element in one position, and inwardly of said element in another position.

2. In a device of the character described; the combination with the end structure of a car, including a drawbar; of a resilient buffering element connected to said end structure and extending outwardly of and spaced from the outer end of said drawbar; said buffering element and said drawbar being arranged substantially within a horizontal plane; a block swiveled to said drawbar and extending to a point beneath said resilient element;

and a coupling element pivotally mounted on said block.

3. In combined buffering and coupling means associated with the end structures of adjacent cars, said buffering means including a bowed resilient element rigidly secured to the end structure of each of said cars, said resilient elements being oppositely disposed and spaced outwardly from the end structure of the car to which it is affixed; of a drawbar for each car having an end portion projecting beyond the end of the car structure to which it is affixed and arranged within the bowed portion of the adjacent resilient element; and a coupling element operatively associated with each of said drawbars and arranged to extend outwardly of its related resilient element in one position, and inwardly of said element in another position; said coupling elements having their free end portions constructed for detachable swingable engagement, whereby upon approach of said resilient buffering elements said coupling elements automatically yield to permit said approach; and upon separation of said buffering elements said coupling elements resume position to effect draft connections between said drawbars.

4. In a device of the character described, the combination with the end structure of a car, including a drawbar; of a buffering element extending outwardly of and spaced from the end of said drawbar, said element extending to either side of said drawbar and being connected to said end structure; and coupling means having a universal connection with said drawbar and including a coupling element movably arranged to swing outwardly beneath said buffering element to operative position and being swingable to a point within the plane defined by the buffering element when in inoperative position.

In witness that I claim the foregoing I have hereunto subscribed my name this 26th day of September, 1923.

JOHN F. O'CONNOR.
